UNITED STATES PATENT OFFICE

ANSON K. BRADLEY, OF WORCESTER, MASSACHUSETTS, ASSIGNOR TO MORGAN CONSTRUCTION COMPANY, OF WORCESTER, MASSACHUSETTS A CORPORATION OF MASSACHUSETTS

GAS PRODUCER

Application filed June 7, 1928. Serial No. 283,562.

The present invention relates to gas producers, and more particularly involves an arrangement for controlling closely the mechanical removal of ashes from the producer, 5 in such a manner as to adapt the rate and duration of ash removal to the actual condition of the fuel bed within the producer. The invention is embodied in a construction which can be made to secure the rapid discharge of a large volume of ashes in a short period of time, as is sometimes required under certain conditions of producer operation, or which can be made to secure a more or less slow and continuous discharge of ashes, if 10 such a mode of discharge is best suited to the conditions prevailing in the fuel bed.

The features of my improved construction are fully set forth in the following description and illustrated in the accompanying drawings, in which—

Fig. 1 is a vertical sectional view of a gas producer constructed in accordance with the invention.

Fig. 2 is a large scale fragmentary view illustrating, in side elevation, a differential driving means for the ash pan of the gas producer shown in Fig. 1.

Fig. 3 is a sectional view on the line 3—3 of Fig. 2.

Fig. 4 is a sectional view on the line 4—4 of Fig. 2.

Fig. 5 is a sectional view on the line 5—5 of Fig. 4.

Fig. 6 is a fragmentary plan view of the ash pan, showing the ash-removing plow.

Fig. 7 is a large-scale fragmentary view showing in side elevation certain devices associated with the operation of the plow.

Fig. 8 is a detached view in elevation of adjustment devices for the differential driving means of the ash plow.

Like reference characters refer to like parts in the different figures.

Referring first to Fig. 1, the gas producer therein illustrated provides the usual fuel-containing shell 1 which, in the present construction, is adapted to be continuously rotated at a relatively slow speed, for example, one complete revolution in five or six

minutes. To this end, said shell 1 is rotatably supported on a series of elevated rollers 2, 2, of which only one is shown, these rollers being carried by the stationary columns 3, 3, of which only one is shown. The shell 1 has secured to its outer wall a surrounding ring 4, whose lower surface provides an annular track 5 adapted to run on said rollers 2, 2. The outer peripheral surface of ring 4 is made in the form of an annular gear 6, with which meshes a driving pinion 7, here shown as secured to the upper end of a vertical countershaft 8. At its lower end said shaft 8 carries a bevel gear 9 which is in mesh with a bevel gear 10 on a driving shaft 11, the latter being rotated continuously, at an appropriate speed, during the operation of the producer from any suitable source of power, such as reduction gearing, not shown, connecting it with motor 12. The columns 3 provide for the stationary support of the top or cover section 13 of the producer, which has the usual depending annular skirt 14 that projects into the water jacket 15 surrounding the shell 1, thereby to form a water seal between the shell 1 and the cover section 13, allowing the former to rotate relative to the latter without escape of gas.

An ash pan 16 disposed below the lower open end of shell 1 is adapted to contain a body of water of sufficient depth to form a water seal with an annular depending skirt 17 of said shell, as is usual in rotary water seal gas producers. Said ash pan 16 is supported for rotation independently of said shell, as for instance, upon ball bearings 18 interposed between an annular hub 19 on the bottom of said pan and a stationary base member 20. The ash pan 16 has a central opening therethrough for the passage of a blast of air and steam to the interior of the producer, the blast being supplied by a suitable blower 21 and the central opening through the pan being surrounded by an upwardly projecting flange or hub 22 which supports a blast distributing hood 23 of ordinary construction. The flange or hub 22 has an annular lateral extension 24 which serves as a pivotal bearing for a laterally

projecting curved plow arm 25, which latter lies flat on the bottom of ash pan 16 and is adapted, in the absence of restraint, to partake of any rotary motion to which said pan 16 is subjected. Near its outer end said plow 25 provides a raised lug 26 for cooperation with the end of a rocking member 27 which is supported in suitable bearings 28, 28, on the wall of rotary shell 1. From the upper end of member 27 projects a lever arm 29, by which said member 27 can be rocked in its bearings to move its lower end into and out of the path of the lug 26 on plow 25.

In the position of the parts shown in Figs. 1 and 6, the member 27 has been rocked into an operative position, so that its lower end, in the rotation of shell 1, will engage the lug 26, to cause rotation of the plow 25 in unison with the rotation of the shell; this operative position is yieldingly maintained by the engagement of the free end of lever arm 29 with a hook or latch 30, pivoted at 31 on the outside of shell 1, as shown in Fig. 7. A counterweight 32 normally holds the hook or latch down, thereby preventing member 27 from turning in its bearings 28, 28; thus the plow 25 is constrained, under these conditions, to rotate at the same speed as that at which the shell itself rotates, so long as no abnormal or excessive resistance to such rotation of the plow 25 is encountered. However, in the event of such excessive resistance, the torsion communicated to member 27 by lug 26 will exert itself through arm 29, in a direction to raise the pivoted hook or latch 30 and its counterweight 32, until said arm 29 is released, allowing said member 27 to swing in its bearings 28, 28, until its lower end clears the lug 26 on plow 25. The above described mechanism, for the detachable connection of the ash plow 25 to the rotating fuel shell 1, is shown here in substantially the same form as it appears in my prior copending gas producer application Serial No. 138,039, filed September 27, 1926, and said mechanism, of and by itself and apart from its relation to the devices hereinafter described, is not the subject matter of the present invention. Said invention resides, in part, in the correlation of the above described mechanism to a variable speed drive for the ash pan 16, as will now be fully described.

As shown in Figs. 1 and 3, the constantly rotating driving shaft 11 has keyed thereto an annular differential driving member 33, which is interposed on said shaft between a braking member 34 and a driven member 35, said two last-named members being mounted for independent rotation on bushings 36, 36, surrounding said shaft 11. The opposing faces of members 34 and 35 provide annular bevel gears 37 and 38 respectively, with each of which mesh a plurality of bevel pinions 39, 39 (here shown as four in number). Each

of these bevel pinions 39 is mounted for free rotation on a radial shaft 40 carried by suitable bosses 41, 41 of the driving member 33, the rotation of which carries the pinions 39, 39 in an annular path in rolling contact with the gears 37 and 38, thereby to impart rotary movement to both of the members 34 and 35, the proportion of such movement which each receives being in inverse ratio to the resistance or drag which is imposed upon each against such rotary movement. Such resistance or drag is made variably effective on the member 34 through the medium of a brake drum 42, forming part of said member, and encircled by a brake band 43. One end of said band 43, as shown in Fig. 8, is secured to a fixed point 43', and the other end is fastened to one arm 44' of a lever 44 pivoted at 45. The band 43 is tightened or loosened by movement of the other arm of lever 44, which for this purpose is connected by a screw and nut 46 to a brake-actuating shaft 47, here shown as equipped with a hand wheel 48 disposed conveniently above the operating platform 49 of the gas producer.

The other differentially driven member 35, rotatably mounted on shaft 11, has its hub 50 connected to the hub of a bevel pinion 51, the latter being in mesh with an annular bevel gear 52 secured in any suitable way to the under side of ash pan 16. In this manner, the ash pan 16 takes its speed of rotation from the proportionate amount of rotation imparted to the member 35 by the differential drive,—the ratio of gearing being preferably such that with member 35 rotating at maximum speed (brake band 43 holding the member 34 stationary), the ash pan 16 will rotate at twice the speed of the fuel shell 1. As the brake band 43 is loosened, to gradually decrease the retardation of member 34, the proportion of the rotative movement imparted by the differential mechanism to the ash pan 16 is gradually reduced,—and thus by manipulation of the devices which control the setting of said brake band 43, any speed of said ash pan 16, below the aforesaid maximum speed, is obtainable.

However, to prevent too low a speed of ash pan rotation, means are provided to insure the rotation of member 35 at a speed not less than the speed of driving member 33. As shown in Figs. 4 and 5, the radial spokes 53 of member 33 provide projections 54, 54, which are adapted to engage with pawls 55 projecting inwardly from the member 35. Each pawl 55 is pivoted to swing on an axis 56 provided by the member 35; and is held in position to be engaged by the projections 54, 54, through the medium of a spring 57. Regardless of how loose the brake band 43 may be, the rotation of member 33 always operatively carries the projections 54, 54, against the pawls 55, 55, to rotate the member 35 at a minimum speed corresponding to the

speed of member 33, and the ratio of gearing is such that this minimum speed produces rotation of the ash pan 16 at a speed equal to or slightly greater than the speed of the fuel shell 1. The projections 54, 54, and the pawls 55, 55, do not interfere with a greater speed of the member 35, such as is produced when the brake band 43 is tightened, because under these conditions, the member 35 can run ahead of the member 33, and when a pawl 55 overtakes one of the projections 54, the advancing bevel edge 58 of said pawl strikes a bevel surface 59 on the projection, thereby depressing said pawl so that it passes the projection. Once past the projection, the pawl resumes its normal position, due to the action of spring 57.

In operation, with the brake 43 adjusted to give the ash pan a somewhat higher speed than the fuel shell 1, the consequent cleavage or shearing action occurring in the mass of fuel and ash will cause the ashes, if accumulated high on the inner wall of the producer, to descend into the pan,—and such descent will occur, without regard to the operating condition of the plow 25. If the latter, under these circumstances, is engaged by the member 27, the consequent pronounced relative movement between pan 16 and plow 25 will push the ashes rapidly outward, and up the inclined end 60 of said plow, for relatively rapid removal by a stationary skimmer 61, projecting over the rim of the pan. And the rate of such ash removal, as well as the rate of the ash descent within the producer, will be increased or decreased, as the speed of pan 16, through adjustment of the brake 43, is increased or diminished.

On the other hand, if the latch 30 is rocked up into an inoperative position, the member 27 is no longer effective to hold the plow 25 to the slow rotation of the shell 1. Under these circumstances, the outward crowding of ashes will proceed at a much slower rate, under the influence only of the gradual descent of ashes into the pan,—and the rate of ash removal will be relatively slow.

I claim:

1. In a gas producer, a rotary fuel shell and a rotary ash pan, a common actuating means for said parts, gearing connecting said actuating means to said shell, for rotation of the latter at a constant speed, differential gearing connecting said actuating means to said pan, means for braking one of the members of said gearing, to vary the speed of the pan-driving member of said gearing, thereby to procure rotation of said pan at varying speeds, higher than the speed of said shell, an ash plow rotatably mounted in said pan, and means operable selectively to connect said ash plow to, or to disconnect it from, said shell.

2. In a gas producer, a rotary fuel shell

and a rotary ash pan, a common actuating means for said parts, gearing connecting said actuating means to said shell, for rotation of the latter at a constant speed, differential gearing connecting said actuating means to said pan, means for braking one of the members of said gearing, to vary the speed of the pan-driving member of said gearing, thereby to procure rotation of said pan at varying speeds, means for insuring the rotation of said pan by said actuating means, irrespective of the adjustment of said differential drive, at a minimum speed, not less than the speed of said shell, an ash plow rotatably mounted in said pan, and means operable selectively to connect said ash plow to, or to disconnect it from, said shell.

3. In a gas producer, a rotary fuel shell and a rotary ash pan, a common actuating means for said parts, gearing connecting said actuating means to said shell, for rotation of the latter at a constant speed, differential gearing connecting said actuating means to said pan, means for braking one of the members of said gearing, to vary the speed of the pan-driving member of said gearing, thereby to procure rotation of said pan at varying speeds, whereby to produce more or less shearing in the bed of fuel with a corresponding descent of ashes into said pan, an ash plow rotatably mounted in said pan, and adapted by the pressure thereon of the fuel, to rotate in unison with said pan, thereby to produce only such removal of ashes as is caused by the aforesaid descent of ashes, and means for connecting said ash pan to said shell, for rotation in unison therewith, whereby the rate of ash removal is increased.

Dated this first day of June, 1928.
